(57) **CLAIM**

The ornamental design for a dental matrix band, as shown and described.

DESCRIPTION

FIG. 1 is a front elevation of a dental matrix band showing my new design;

FIG. 2 is a top plan view thereof;

FIG. 3 is a side elevation thereof;

FIG. 4 is a side elevation of the side opposite that shown in FIG. 3;

FIG. 5 is a bottom plan view thereof;

FIG. 6 is a rear elevation thereof; and,

FIG. 7 is a front perspective view thereof shown on an enlarged scale.
